ADJUSTABLE CABLE FASTENER FOR SKI
BINDING

Howard Jansen, Chicago, Ill.

Application September 13, 1946, Serial No. 696,753

4 Claims. (Cl. 280—11.35)

1

This invention relates to improvements in ski bindings, and has particular reference to a novel adjustable heel cable fastening device.

This invention is particularly concerned with, but not necessarily limited to, ski bindings of the type having some form of releasable clamping means associated with the sole of the ski boot and a resilient cable passing around the heel of the boot to hold the boot firmly engaged in such clamping means and against a toe stop on ski as shown in my prior Patent No. 2,338,249. In such bindings the resilient heel cable holds the ski boot in place to maintain a clamping engagement between the sole of the boot and the ski, while at the same time permitting a certain latitude of foot movement whereby the heel may be raised in normal walking and skiing movements without allowing the boot to become detached from the ski. In order to remove the ski from the boot the heel cable must be released and disengaged from the heel to permit rearward movement of the boot on the ski to release the sole clamping means. In putting on the skis this operation is reversed, first sliding the boot into the sole clamping means and against the toe stop, and then tensioning the resilient cable against the heel of the boot. The cable fastener operates to tension the cable to hold the boot in such clamped position until it is manually released.

The general object of the present invention is to provide a novel and improved adjustable cable fastener for the heel cable of a ski binding of the type described. Other objects are to provide an inexpensive and rugged cable fastening and tensioning device which may easily and quickly be tightened and released in putting on and taking off the skis, and which may readily be adjusted to different lengths to apply the proper cable tension on ski boots of different sizes without altering the length of the cable. Still other objects are to provide an adjustable fastening device of the type described which is strong and positive in action, which does not introduce any obstruction or impediment in the use of the skis, and which is designed to avoid improper release in normal skiing.

These and other objects will become apparent as the description proceeds in connection with the accompanying drawings illustrating certain preferred embodiments of the invention. It is to be understood, however, that the drawings are merely for the purpose of illustrating the principles of the invention and are not to be taken as in any way limiting the spirit or scope of the invention.

2

In the drawings:

Figure 1 is a perspective view of a portion of a ski and ski boot illustrating a binding constructed in accordance with the present invention;

5 Figure 2 is a plan view of the ski portion shown in Figure 1 with the boot removed therefrom;

Figure 3 is an enlarged sectional view of the cable fastener taken on the line 3—3 of Figure 1;

10 Figure 4 is a cross sectional view taken on the line 4—4 of Figure 3;

Figure 5 is a perspective view of the guard member for the cable fastener; and

15 Figure 6 is a side view with certain parts broken away of an alternative form of cable fastening device embodying the principles of the invention.

In the present construction the heel cable of the binding forms an endless loop having a rear portion engaging behind the heel of the ski boot and a front portion arranged to be tensioned by 20 an over-center clamping lever a short distance in front of the toe of the boot. A series of notches in an upstanding plate on the ski provides a plurality of fulcrum points for the pivot pin of the clamping lever in different positions to effect 25 the proper cable tension for boots of different sizes without shortening or lengthening the cable. A flexible guard member covers the open ends of the notches to keep the pivot pin of the lever in the notch in which it is placed, but at the same time permitting the pin to be moved from one notch to another when desired. The clamping lever has a free end which may be raised to provide sufficient slack in the heel cable to release the ski boot from its sole clamps. When the 30 clamping lever is pressed forwardly and downwardly against the top surface of the ski the heel cable is tensioned in accordance with the notch in which the pivot pin has been placed, which tension is directed in a line below the center of the pin to hold the lever in locked position with its extremity bearing against the ski surface so as to present no projection which might cause its accidental release.

35 In Figure 1 the numeral 10 designates a portion of a ski having a boot 11 secured thereon by a ski binding of the type referred to hereinabove in general terms. Opposite sides of the sole of the boot in the present instance are provided with cleats 12 having rearwardly and upwardly sloping grooves 13. Adjustably attached to the ski are 40 a pair of bracket arms 14 having short inwardly directed tongues 15 engageable in the grooves 13. These bracket arms have base portions on the ski with elongated slots for receiving screws 16 to allow sufficient adjustment of the 45

bracket arms to accommodate the usual range of sizes of ski boots so that the cleats 12 will fit properly between the bracket arms with the tongues 15 holding the sole of the boot down firmly against the ski when the boot is in its proper position. The bracket arms are carefully adjusted on the screws 16 to allow the boot to twist off the ski to the right or left, and such adjustment is maintained by small nails 19 to prevent the bracket arms from moving under the screw heads. The arrangement of these parts is such that the ski boot may be fastened to the ski by merely sliding the boot forwardly on the ski between the bracket arms 14 until the toe of the boot engages a toe stop 17, in which position the parts will be disposed as shown in Figure 1 with the tongues 15 riding in mid portions of the grooves 13 to clamp the sole of the boot firmly against the top of the ski. Screws 18 provide sufficient mounting adjustment for the toe stop 17 to fit a particular ski boot.

The toe stop 17 differs from that shown in my prior patent above referred to in that it comprises a single vertical or upstanding transverse stop flange 40 having a continuous rigid connection at 41 across the forward edge of its horizontal base portion 42 which is attached to the ski in the manner described. The stop flange has a horizontal curvature and its upper edge has a rearwardly curved lip 43 to engage over the sole of the boot, as shown. The present toe stop may be used as a sole clamp with suitable heel clamping means to constitute the entire ski binding, making the side cleats 12 and brackets 14 unnecessary for ordinary skiing, whereas the side cleats and brackets must be used with the type of open top toe stop disclosed in my prior patent. Either with or without the side cleats and brackets, the present toe stop affords an easy and quick release in a fall because it does not confine the toe of the boot as does the conventional strap type of toe clamp. The horizontal and vertical curvatures of the stop flange 40 securely grip the boot sole for ordinary skiing but release it in a severe twist to prevent injury to the wearer in a fall.

The above described clamping engagement is maintained by a resilient cable 20 which passes through a curved tubular spring member 21 around the heel of the boot, it being understood that the boot heel is grooved to hold the cable in the position shown. Cable guides 22 on opposite sides of the ski direct the cable tension not only forwardly but also downwardly to tend to hold the ski up against the heel of the boot when the foot is lifted, but the resilience of the cable allows the boot heel to raise in walking movements.

The forward end of the cable forms a bight 23 trained through a curved guide sleeve 24 pivotally mounted in the cable clamping lever 25. The clamping lever 25 terminates at its forward free end in a flat tongue 26 adapted to lie against the top of the ski when the device is clamped and to provide a finger piece for manipulating the lever to clamp or unclamp the cable. The lever 25 is of inverted channel shape having side flanges which carry the sleeve 24 and terminate in a pair of side arms 27 carrying a fulcrum pin 28 which forms a center of rotation for the lever in its clamping and unclamping movements as shown in Figure 1. The fulcrum pin 28 may be set in any one of a series of notches 30 at different distances from the toe plate, which notches are formed in the upstanding parallel side flange plates 50 of a rigid channel element 31 secured

to the top of the ski by a plurality of screws 32, 33 and 34. In the embodiment shown in Figure 1 the notches 30 are formed on an inclined forward edge 51 of the element 31, with the side walls of these notches, which fulcrum the pivot pin 28, being inclined rearwardly from the vertical so that the cable tension will maintain the pin seated in the bottom of the notch when the binding is clamped.

A spring metal guard 35 of the form shown in Figure 5 covers the open ends of the notches 30 to prevent casual displacement of the pivot pin 28 from its notch when the binding is unclamped. This guard has a hole 36 adapted to be secured under the head of screw 33, and an elongated slot 37 providing a degree of longitudinal adjustment for the other end of the guard under the head of the screw 34 when the guard is installed so that the guard may thereafter be sprung up sufficiently to move the pin 28 from one notch to another without requiring the loosening of any of the screws.

In Figure 1 it will be seen that the pivot pin 28 is positioned in an intermediate one of the notches 30, the clamped position of the lever 25 being shown in full lines and the released position being shown in broken lines. By virtue of the fact that the cable guides 22 are positioned below the top surface of the ski, the cable tension securely holds the lever 25 in overcenter position with the tongue end 26 bearing against the top of the ski in clamped position regardless of whether the fulcrum pin is moved to a lower or a higher notch. In clamped position the top surface of the tongue 26, as well as the top surface of the main body portion of the lever 25, forms a smooth ramp which cannot become accidentally caught and raised to release the binding. When the clamping lever is raised through the arc 29 to the broken line position, sufficient slack is produced in the cable 20 to permit the boot heel to become disengaged from the spring member 21, thereby to permit the release of the boot also from the sole clamps.

The curved sleeve 24 passes through openings in the side flanges of the lever 25 to provide a curved guide and bearing for the cable 20 in the lever to accommodate the relative twisting motion between the cable and the lever when the lever is swung on its pivot. This sleeve also prevents sharp bends in the bight 23 when the cable is tensioned to the position shown in Figure 2 and permits sliding of the cable to equalize the tension on opposite sides without sliding around the heel.

Figure 6 illustrates an alternate form of the cable clamping device wherein the channel member 31a has its notches 30 arranged in horizontal top edges 52 of its flange plate 53. The cable bight 23 drops to an overcenter position when the device is clamped, and the guard 35a prevents displacement of the fulcrum pin 28 from the slot in which it has been placed. The guard 35a may be sprung upward to move the fulcrum pin from one notch to another in adjusting the binding to a particular boot length. The other parts shown in Figure 6 corresponds to the embodiment first described and bear the same reference numerals.

It is, of course, understood that the present cable fastener may be used with other forms of sole clamps as it is intended for use with any binding having a resilient heel cable.

In a fall, the skier's body usually starts to roll over, while the skies, because of their length and

digging into the snow, are prevented from similarly rolling, resulting in a twisting of one or both of the skier's legs. Upon such an application of torque to the ski binding, the boot will pivot laterally about one or the other of the tongues 15, causing the other side of the boot to swing rearwardly sufficiently to disengage the groove 13 from its tongue 15. Upon disengagement of one sole cleat from the corresponding bracket arm, the sole of the boot is free to shift laterally above that bracket arm and disengage the boot from the tongue 15 about which the pivotal movement occurred. The boot is thereby also free to disengage from toe stop 17, relieving the heel cable tension and detaching the boot from the ski.

In a forward fall, the boots tilt forwardly, pivoting about the toe portions and stretching the heel cables. Continuation of this movement lifts the boot up off the tongues 15, owing to the downward slope of the grooves 13, and allows the toe to move out of engagement with the toe stop. The amount of force required to effect such emergency automatic disengagement of the boots from the skis is regulated by adjusting the tension of the heel cables. Thus, the heel cables may be loosened to produce emergency release before the skier has completed his fall, or they may be tightened to delay the release until considerable stress is developed.

The use of the present type of toe stop 17 in a binding having heel tensioning means but no side cleats and brackets is disclosed and claimed in my continuation-in-part application, Serial No. 753,709, entitled Ski Binding, filed June 10, 1947.

Various other changes in the construction and arrangement of parts will occur to persons skilled in the art, and all such modifications within the scope of the appended claims are included in the invention.

Having now described my invention and in what manner the same may be used, what I claim as new and desire to protect by Letters Patent is:

1. In a shoe clamping device, an over-center pivotal lever for tensioning shoe engaging means, a channel shaped member having upstanding flanges and a series of notches in said flanges for pivotally mounting said lever in different positions to clamp shoes of different sizes, an elongated resilient guard extending sufficiently closely over said notches and the pivotal mounting of said lever to hold said lever releasably in any selected notch against casual displacement, and means for securing the ends of said guard to said channel member beyond the ends of said series of notches to provide flexibility in the portion of said guard over said notches for shifting said lever from one notch to another.

2. In a shoe binding, a pivotal over-center lever for tensioning the binding, an elongated member having a series of notches forming fulcrum points for said lever, and an elongated strip of spring

metal extending over said notches to hold said lever in any selected notch, said strip having ends secured to said member at a distance from the end notches and having a flexible portion between said secured ends of greater length than said series of notches to release said lever from any one of said notches for shifting the lever to a different notch.

3. In a ski binding, a pivotal over-center lever for tensioning the binding, an elongated member having a series of notches forming fulcrum points for said lever, an elongated strip of spring metal extending over said notches to hold said lever in any selected notch, said strip having ends secured to said member at a distance from the end notches and having a flexible portion between said secured ends of greater length than said series of notches to release said lever from any one of said notches for shifting the lever to a different notch.
- 10 4. In a shoe binding, a pivotal over-center lever for tensioning the binding, an elongated member having a series of notches forming fulcrum points for said lever, an elongated strip of spring metal extending over said notches to hold said lever in any selected notch, said strip having ends secured to said member at a distance from the end notches and having a flexible portion between said secured ends of greater length than said series of notches to release said lever from any one of said notches for shifting the lever to a different notch, means for adjusting the secured position of one end of said strip to vary the spring action of the strip, and a transverse curved sleeve pivotally mounted on said lever to receive a cable of the binding.
- 15 5. In a shoe binding, a pivotal over-center lever for tensioning the binding, an elongated member having a series of notches forming fulcrum points for said lever, an elongated strip of spring metal extending over said notches to hold said lever in any selected notch, said strip having ends fixedly secured to said member in fixed positions at a distance from the end notches and having a flexible portion between said secured ends to release said lever from any one of said notches for shifting the lever to a different notch, and means for making semi-permanent adjustment of the secured position of one end of said strip to hold said strip sufficiently close to said notches to require intentional manipulation of said lever to
- 20 30 35 40
- shift the lever out of any one of said notches and prevent casual shifting of the lever when the lever is operated to release the tension on the binding.
